Bazilla Harrington

UNITED STATES PATENT OFFICE.

BARZILLA HARRINGTON, OF BOSTON, MASSACHUSETTS, ASSIGNOR TO
HIMSELF AND J. L. NEWTON, OF SAME PLACE.

IMPROVED KNIFE FOR REMOVING HAIR FROM HIDES.

Specification forming part of Letters Patent No. 56,144, dated July 3, 1866; antedated June 22, 1866.

To all whom it may concern:

Be it known that I, BARZILLA HARRINGTON, of Boston, in the county of Suffolk and State of Massachusetts, have invented a new and Improved Short-Hair Knife; and I do hereby declare that the following is a full and exact description thereof, reference being had to the accompanying drawings, and to the letters of reference marked thereon, making a part of this specification, of which—

Figures 1 and 2 represent opposite side views of the knife with guard attached; Fig. 3, a side view of the knife without guard, showing the dovetailed rib; Fig. 4, the underside view of guard removed from the knife; Fig. 5, a section of guard and knife.

The letter *a* represents the handle; *b*, the blade; *c*, its dovetailed rib; *d*, the guard; *e*, its dovetail groove; *f, f*, its outer sides.

To enable others skilled in the art to make and use my invention, I will proceed to describe its construction and operation.

It is well known that in the process of converting green hides with the hair on into leather a large percentage of the hides are cut or so injured in the process that they are reduced from the first quality to a lower grade, and thus a loss is occasioned. It is well known, also, that after the hair has been removed by the usual process of liming and rubbing it off there remains a short fine hair or fur, and also hair on the edges and extremities of the hide, which has to be removed by a sharp knife or other instrument, called the "short-hair knife."

Now, the chief mischief is done to the hides in removing this fine hair by cutting or chipping the grain of the hide, and my invention is to prevent the possibility of cutting the hide, and at the same time furnish an equally good instrument for accomplishing the purpose, and I will explain the same.

The accompanying drawings give an accurate idea of the knife. It is made of steel, like ordinary knives, with the ordinary handle; but for convenience I make the blade with a double edge, as seen in Fig. 5, the under side of which is somewhat convex, being thickest in the middle and gradually decreasing in thickness to the edge. The upper side of the blade has a dovetail rib (marked *c* in the drawings) in the middle or thick part of the blade, and from this rib to the edge on either side the blade is somewhat concave.

Fig. 5 clearly shows the form of the blade. Figs. 4 and 6 show the form of the guard, which is made with a dovetail groove, (marked *e*), so as to slip closely onto the rib *c*. Figs. 2, 4, and 6 clearly show its form. It is made of German silver, or brass, or copper, or any suitable metal or material. It should project beyond the edge of the blade about the sixteenth part of an inch. Its edges should be thick enough, or slightly corrugated on the inner side, so as to give it requisite stiffness.

When the knife needs sharpening the guard may be easily slipped off and also ground down if necessary.

I use the knife in the same way as I use the ordinary knife,

The concave side of the blade and the openings of the guard allow the hair to pass off without inconvenience.

The blade and guard may be cut and stamped into shape by machinery.

The rib may be riveted onto the blade, or made solid, by rolling it down when hot on either side.

The expense of the knife will be slightly above the ordinary knife.

I do not confine myself to the method described of fastening on the guard. It may be done by dispensing with the rib and the groove and inserting the end of the guard into the handle by a slit in the handle, and also in the guard, held fast by a pin, and at the other end by a screw passing through the guard into the blade, or other convenient way.

This form of knife will be invaluable in cleaning kid-skins for gloves, where so much care is needed to prevent chipping the grain of the kid.

I claim, also, that a like combination and arrangement of blade and guard may be applied to other cutting or edged instruments.

What I claim as my invention, and desire to secure by Letters Patent, is—

A short-hair knife, with its form of blade *b*, its rib *c*, and its guard *d*, combined and arranged substantially as and for the purpose above set forth.

BARZILLA HARRINGTON.
